LIQUID RECEPTACLE SUPPORT

Thomas W. Casey, Akron, Ohio, assignor to
Seiberling Latex Products Company, Akron,
Ohio, a corporation of Ohio

Application November 12, 1934, Serial No. 752,651

3 Claims. (Cl. 150—1)

This invention relates to supports for liquid receptacles such as are used with syringe attachments and the like and has for its primary object to provide a device which is simple in construction, efficient in its purpose and inexpensive to manufacture.

Receptacles of the type referred to as now in use are usually made of rubber or metal and are provided with tabs, rings or hooks by which they are supported upon walls or other suitable structures. It is further necessary to have a hook or nail provided upon the wall to receive the tab or ring of the receptacle and this is rather unsightly when not in use. Furthermore, the hook or nail cannot be withdrawn without leaving a mark on the wall and consequently when the hook or nail is once driven in, the receptacle must always be supported in the same location. This, of course, is quite a handicap as very frequently it is impossible for different persons to utilize the same location for the receptacle. It is furthermore desirable to position the receptacle at different heights upon the wall or other structure, and the manner of supporting the receptacle up to the present time has made this feature more or less impracticable. Then, again, with walls being constructed of tile and similar materials as the tendency now is, it is practically impossible to drive a nail or hook into these walls without the danger of cracking the same.

It is therefore a further object of the present invention to provide a suitable supporting means for the receptacle which will entirely eliminate all of the aforementioned objections and at the same time afford ample security for supporting the receptacle at any desirable location upon a wall or other structure.

More specifically the invention resides in providing a vacuum device suitably connected to the receptacle and which may be secured upon practically any surface and in any location without marring the surface and without danger of possible accidental disengagement.

With the objects above indicated and other objects hereinafter explained in view, the invention consists in the construction and combination of elements hereinafter described and claimed.

Referring to the drawing,

Figure 1 is a front elevational view of one type of receptacle embodying the present invention;

Figure 2 is a transverse sectional view taken on line 2—2 of Figure 1 and showing one manner of detachably connecting the vacuum device;

Figure 3 is a transverse sectional view similar to Figure 2 but showing a different manner of detachably connecting the vacuum device;

Figure 4 is a transverse sectional view similar to Figure 2 but showing a still different manner of detachably connecting the vacuum device;

Figure 5 is a transverse sectional view similar to Figure 2 but showing the vacuum device integrally connected to a receptacle; and

Figure 6 is a front elevational view of a combination receptacle embodying the invention.

In the drawing, 10 indicates a liquid receptacle of the well-known open mouth type and in this instance is made of rubber material in any desired manner. This receptacle 10 of course, may be formed in any shape and made of any other desirable material including various kinds of metal, depending upon the purpose for which it is intended.

The receptacle 10 is, of course, hollow so that it will hold liquid and at the lowermost end there is a tubular extension 11 adapted to receive one end of a hose 12, the opposite end being connected with any desired instruments such as a syringe (not shown). The upper portion of the receptacle 10 is formed with an open mouth 13 having a circumferential bead 14 at its outer end to reinforce the same and the liquid may be introduced through this mouth into the interior of the receptacle in any desired quantity.

A tab 15 extends upwardly from and is secured at its lower end, preferably integral, to the bead 14 at one side of the mouth and has a reinforcing rib 16 extending around its free edge. An opening 17 is provided in the tab 15 by which the receptacle 10 is ordinarily supported. Thus far the description is of a standard type or rubber water bag for use with a syringe or similar device. There are, of course, many other types of such receptacles with which the present invention may be embodied and therefore the one illustrated and described herein is for the purpose of simplifying the understanding of the invention.

In Figures 1 and 2, one form of the supporting device embodying the present invention is illustrated. A vacuum cup 18 of suitable size has a recessed portion 19 adapted to be pressed against a wall or other supporting structure and is maintained thereon by the suction or vacuum created in the recessed portion. The opposite side of the vacuum cup 18 has a sleeve 20 secured therein which is interiorly screw-threaded. A thumb screw 21 has a threaded shank which extends through the opening 17 provided in the tab of the receptacle 10 and removably cooperates with the threads of the sleeve 20. The outer end of the thumb screw 21 has a head or enlarged lateral flange 22 preferably formed integral therewith and is adapted to abut the body of the tab around the opening 17. The flange is knurled so that it may be turned to securely clamp the tab between the flange and sleeve to prevent accidental disengagement. The receptacle 10 may be disconnected from the vacuum cup 18 by merely turning the flange 22 in an opposite direction.

until the thumb screw is disengaged from the sleeve.

In Figure 3 a different connection is shown wherein the vacuum cup 18 has on the side opposite to the recess 19 an axial extension 23 formed integral therewith and a head or lateral flange 24 also formed integral with the outer end of the extension. In this arrangement the opening 17 in the tab 15 is stretched over the head or flange 24 and becomes disposed around the extension 23. As the flange 24 is larger in diameter than the diameter of the opening 17, the tab is secured against accidental disengagement. However, the receptacle may be disconnected from the vacuum cup by stretching the opening 17 sufficiently to permit it to pass over the flange 24.

In Figure 4 a still different connection is shown wherein the vacuum cup 18 has on the side opposite to the recess 19 an axial extension 25 formed integral and preferably being slightly tapered. Adjacent the outer end of the extension is a circumferential groove 26 adapted to receive therein a metal washer 27. In this arrangement the opening 17 in the tab 15 is inserted on the end of the extension 25 and the washer 27 is then forced over the end of the extension until it is seated in the groove. The washer is of larger diameter than the opening 17 and consequently the tab is prevented from accidental disengagement from the vacuum cap. However, the same may be readily disconnected by merely removing the washer 27.

In Figure 5 a still different connection is shown wherein the vacuum cup 18 at the side opposite to the recess 19 is integrally united with the upper portion of the receptacle 10 at a location indicated by dot and dash lines in Figure 1. This arrangement has many advantages over the others heretofore described, but principally eliminates the possibility of the vacuum cup becoming lost. Furthermore, the vacuum cup may be formed integral with the tab 15 at the same location as that shown in the other figures or a plurality of such vacuum cups may be employed and located at the opposite upper corners of the receptacle to obtain more than one point of attachment.

In Figure 6 a so-called combination hot water bottle and fountain syringe is shown wherein the receptacle 27 is of rubber material and adapted to contain a suitable liquid for the purpose for which it is intended. One end of the receptacle 27 has a constricted neck portion 28 and an outwardly flared mouth portion 29, the neck portion being provided with an opening 30 through which the liquid may be introduced and which is interiorly screw-threaded to receive a screw-threaded plug 31. Tabs 32 are provided upon the opposite ends of the receptacle and are provided with openings by which the receptacle may be supported. A vacuum cup 18 is integrally united with one wall of the receptacle 27, preferably at a location remote from the inlet end as shown, but it should be understood that this vacuum cup 18 may as readily and effectively be connected to the tab 32 directly opposite to the inlet end in the manner shown in the other figures.

When used as a hot water bottle, the plug 31 is employed as shown to prevent escape of the water therefrom, but when used with a syringe attachment, the plug 31 is removed and the screw-threaded end of the hose 12 is attached in place

thereof with the receptacle supported in the position shown in Figure 6.

In addition to the supporting feature of the vacuum cup 18, it has the further function, when the receptacle is used as a hot water bottle, of 5 heat applied suction when placed over a boil, carbuncle or the like.

As before stated, receptacles of this character as heretofore available have been very unsatisfactory from the standpoint of the user. While 10 tabs and hooks have been provided for supporting the receptacle, it was not possible to attach the receptacle at any location which might be desirable. While it was true that a new nail might be driven into the wall each time the receptacle was 15 to be used, this necessarily resulted in marring or defacing the wall, materially destroying the appearance of the wall. If to avoid this latter result, the receptacle be hung in the same location each time, then it follows that it could not be 20 used effectively by any and all persons for the purpose for which it was intended.

Furthermore, with the advent of tile walls and 25 seamless walls, it was not possible or, at least, desirable to drive nails or other devices into these walls, so that the receptacle, of necessity, was hung upon door knobs or anything available in the room. This, of course, was even more unsatisfactory than the former method.

By the use of the vacuum device embodying 30 the present invention all of these foregoing objections and disadvantages are eliminated and as a result thereof, the receptacles may be attached to practically any type of wall by merely pressing the vacuum cup against the surface on which the 35 receptacle is to be supported. Furthermore, the receptacle, because of this vacuum device, may be attached at any desired height which renders it available for different persons, and when the vacuum cup is removed no mark of any character 40 is left upon the wall. Additionally, the provision of this vacuum cup does not add materially to the cost of the receptacle. Many other advantages are found in the use of receptacles embodying 45 this invention.

While I have described the preferred embodiments of the invention, it should be understood that I am not to be limited thereto inasmuch as changes and modifications may be resorted to without departing from the spirit of the invention as defined in the appended claims.

What is claimed is:

1. A liquid receptacle for fountain syringes and the like comprising a flexible, molded, rubber bag having an inlet opening at its upper portion 55 through which liquid may be introduced and a liquid discharge opening at its lower portion, and a molded rubber vacuum cup integrally united to said bag adjacent said inlet opening.

2. A fountain syringe including a hollow receptacle for liquid, said receptacle consisting of a unitary, flexible, molded rubber structure formed with an inlet opening at one end and an outlet opening at the opposite end and a vacuum cup adjacent said inlet opening.

3. A fountain syringe including a hollow receptacle for liquid, said receptacle consisting of a unitary, flexible, molded rubber structure formed with an inlet and an outlet opening, and a vacuum cup adjacent the end opposite said outlet 70 opening.

THOMAS W. CASEY.
